UNITED STATES PATENT OFFICE.

EDWARD M. LOFTUS, OF ST. PAUL, MINNESOTA.

GAS-BURNER.

No. 870,566.

Specification of Letters Patent.

Patented Nov. 12, 1907.

Application filed November 23, 1906. Serial No. 344,726.

To all whom it may concern:

Be it known that I, EDWARD M. LOFTUS, a citizen of the United States, residing at St. Paul, in the county of Ramsey and State of Minnesota, have invented a new 5 and useful Improvement in a Gas-Burner, of which the following is a specification.

This invention relates to gas burners and more particularly to automatic cut offs for the same, the object being to provide the burner with an automatic cut off 10 that will cut off the flow of gas when the flame is extinguished accidentally, such as being blown out by an ignorant person or by the wind.

This invention consists essentially in providing a gas burner with a casing in which a thermostatic frame is 15 arranged to which is connected a cut off bar working in the bore of the plug, which is adapted to hold the cut off open when the gas is burning and to close the same when the gas is extinguished.

With these objects in view the invention consists in 20 the novel features of construction, combination and arrangement of parts hereinafter fully described and pointed out in the claims.

In the drawings forming a part of this specification:— Figure 1 is a perspective view of my improved burner. 25 Fig. 2 is an enlarged vertical sectional view of the same. Fig. 3 is a section taken on the line 3—3 of Fig. 2.

In the drawing A indicates an ordinary gas bracket provided with an upwardly extending threaded stem A' at its end on which is screwed the threaded socket 30 B' of a plug B which is provided with a bore B² and a cut out portion B³. A tube C is arranged over the plug B provided with a cut away portion C' over the cut out portion B³ of the plug B. An ordinary burner tip C² is arranged in the end of the tube C which extends 35 up above the end of the plug B.

Secured to one side of the tube C is a casing D in which is arranged a thermostatic frame F carrying a bar G which works in a slot B⁴ in the plug and slot C³ of the tube and is provided with an opening G', adapted 40 to register with the bore B² of the plug. The end of the bar extends into the cut out portion of the plug and is provided with an opening G² in which the reduced end H' of the lever H is arranged which is piv-

oted in the cut out portion of the plug above the cut-away portion of the tube so that by pressing on the lever 45 through the opening in the tube the opening in the bar will register with the bore B² of the plug and allow the flow of gas to pass to the burner so that it can be ignited and it will be readily seen that the heat will cause the thermostatic frame to expand and hold the 50 same in an opened position, but if the gas should be extinguished accidentally the thermostatic frame would contract and draw the bar over the bore of the plug and cut off the flow of gas.

From the foregoing description it will be readily seen 55 that I have provided a very novel and simple and cheap burner which can be easily and quickly ignited and one which is very effective in use.

Having thus fully described my invention, what I claim as new and desire to secure by Letters Patent 60 is:—

1. In a gas burner, the combination with a plug provided with a bore and a cut out portion, of a tube arranged over said plug carrying a gas tip, a casing secured to said tube a thermostatic frame arranged in said casing carrying a cut off bar working in a slot in the plug and tube and a lever pivoted in the cut out portion of the plug connected to said cut off bar for the purpose described. 65

2. In a gas burner, the combination with a plug having a bore and a cut out portion, of a tube arranged over said plug provided with a cutaway portion, a gas tip arranged in said tube, a casing secured to one side of said tube, a thermostatic frame arranged in said casing, a cut off bar provided with an opening connected to said frame working in a slot in said plug, and tube, and a lever pivoted in 75 the cut out portion of the plug connected to said cut off bar, for the purpose described.

3. In a gas burner, the combination with a plug provided with a vertical bore, and a transverse slot terminating in a cut out portion, of a tube arranged over said plug provided with a casing, a thermostatic frame arranged in said casing, a cut off bar secured to said frame extending through said slot into said cut out portion, provided with an opening at its end, and an opening adapted to register with the vertical bore of the plug and a lever pivoted to 80 the tube in said cut out portion of the plug, provided with a reduced end working in the opening in the end of the cut off bar, for the purpose described. 85

EDWARD M. LOFTUS.
